UNITED STATES PATENT OFFICE.

BENO LEVY, OF NEW YORK, N. Y.

DISPLAY DEVICE.

Application filed January 29, 1924. Serial No. 689,285.

To all whom it may concern:

Be it known that I, BENO LEVY, a citizen of the United States, and a resident of the city of New York, borough of Manhattan, 5 in the county and State of New York, have invented a new and Improved Display Device, of which the following is a full, clear, and exact description.

This invention relates to improvements in 10 display devices, and more particularly to improved means for supporting figures or dummies in the display of clothing. The invention relates particularly to window display devices and the like in which clothing 15 is supported and draped in natural position as if upon the figure of a human body, and it is the purpose of my invention to provide means to greatly reduce the cost of such display devices so that clothing can be displayed in natural position upon figures costing 20 appreciably less than those heretofore required.

With these and other objects in view, the invention consists in certain novel features 25 of construction and combinations and arrangements of parts which will be more fully hereinafter described and pointed out in the claim.

In the accompanying drawings—

30 Figure 1 is a perspective view illustrating my invention applied to a figure or dummy for displaying male attire;

Figure 2 is a view, partly in elevation but mainly in section, through the center of the 35 lower portion of the dummy or torso of the display device and through the crotch of the trousers, showing the manner of connecting my improved upright to the dummy as well as to the base;

40 Figure 3 is a top plan view of my improved upright member removed.

For lack of a better term I shall refer to the figure or form upon which the clothing is draped as a "dummy" and shall employ 45 the reference character 1 to indicate the dummy of the male figure.

Referring particularly to Figures 1, 2 and 3, the dummy 1 is preferably although not essentially provided with arms 3 and stumps

50 4. As a matter of economy, it is desirable to make these stumps 4 as short as possible and in some cases they might be dispensed with altogether. In connection with the dummy I provide portable artificial legs 5 with shoes 6 and hose 7 thereon, so that in

the display these portable feet and leg portions 5 will be made either to accommodate men's or women's shoes, as the case may be, in accordance with the articles to be displayed.

In constructing my improved device I provide a base 8, which may be circular or otherwise shaped and which is preferably relatively flat and may have tapered edges 60 9, as shown, so as to allow a carpet or rug to be disposed over the same and present a comparatively smooth surface. On the base 8 and at the rear thereof I secure a tubular post 10, and in this post 10 the cylindrical lower end portion 11 of my improved upright 12 is adjustably secured by means of a set screw 13 so as to regulate the height of the standard. The upper end of the standard 65 is bent upon itself, as shown at 14, extending downwardly a desired distance and then 70 curved forwardly, as shown at 15, and provided with an upwardly projecting lug 16 positioned in a fixed sleeve 18 in the crotch of the dummy 1 and secured therein by a set screw 19 to rigidly support the dummy 80 in an upright position.

It is, of course, to be understood that in draping the figure, the coat and vest of a garment or an overcoat can be readily positioned over the shoulders of the dummy, but, 85 in addition to this, my improved dummy facilitates the proper position of the trousers, as indicated by the reference numeral 20. The upper portions of the trousers are positioned around the lower portion of the dummy and enclose the downwardly curved portion 15 of upright 12, the legs of the trousers receive the stumps 4 of the dummy and the lower ends of the trousers are positioned 90 over the artificial legs, as clearly shown in 95 Figure 2.

Various slight changes and alterations might be made in the general form of the parts described without departing from my invention, and hence I do not limit myself 100 to the precise details set forth but consider myself at liberty to make such slight changes and alterations as fairly fall within the spirit and scope of the appended claim.

I Claim:

A display device comprising a body portion with its upper part having the general outlines of a person's body and its lower part the upper portion of two legs, a base, 110 an upright post fastened to one side of the

base and extending upwardly to slightly above the waistline of the body portion of the device thence downwardly to the crotch and fastened at its end to said body to support the same, loose shoe display freely movable to different positions of the base whereby trousers to be displayed on said body

may readily be placed on the same for display by passing the waist band up between the upwardly and downwardly extending portions of the upright post and the legs of the trousers over the severed legs of the body and the shoe display devices on the base. ¹⁰

BENO LEVY.
